CLAIM

The ornamental design for a pet bowl, as shown and described.

DESCRIPTION

FIG. 1 is a top perspective view of a pet bowl, showing my design.

FIG. 2 is another top perspective view thereof.

FIG. 3 is bottom perspective view thereof; and,

FIG. 4 is a cross-sectional view along a view line intersecting a middle of the pet bowl in FIG. 2.

The broken lines in the drawings depict environmental structure and boundaries and form no part of the claimed design.
